UNITED STATES PATENT OFFICE.

SAMUEL B. WILSON, OF LEXINGTON, KENTUCKY.

OPERATING ATTACHMENT FOR COMPUTING-MACHINES.

1,314,844.

Specification of Letters Patent.

Patented Sept. 2, 1919.

Application filed May 11, 1916. Serial No. 96,825.

To all whom it may concern:

Be it known that I, SAMUEL B. WILSON, a citizen of the United States, and residing at Lexington, in the county of Fayette and State 5 of Kentucky, have invented a certain new and useful Improvement in Operating Attachments for Computing-Machines, of which the following is a specification.

My present invention relates to foot operated attachments for computing machines, such as adding machines, by which the recording of numerals may be set, by action of the foot upon a treadle, in operative relation to mechanism attached to the operating 15 lever of the machine.

The principal object of my invention is to provide an attachment of the character described which will effectively actuate the machine lever by pressure brought upon a 20 suitable treadle, without undue wear on the parts of the machine, or danger of the machine being marred, and without liability of its side walls, adjacent the operating lever, becoming broken if made of glass, as is now 25 in common practice.

Other objects of my invention are to provide an attachment for computing machines which is inexpensive to manufacture, simple and durable, and one which can be quickly 30 adjusted to various types of machine stands.

Further objects of my invention will appear in the following detailed description taken in connection with the accompanying drawing, and forming a part of the specification, and in which drawing:

Figure 1 is a perspective view of a computing machine mounted on a suitable stand, and showing an attachment constructed according to my invention in operative relation thereto.

Fig. 2 is an enlarged rear elevation of the operating lever of a computing machine, showing a coupling in operative relation thereto.

Fig. 3 is an enlarged sectional view on the line 3—3 of Fig. 2.

Fig. 4 is a perspective view of said coupling.

Fig. 5 is a view partly in plan and partly 50 in section showing the treadle and its mounting.

Fig. 6 is a fragmentary perspective view of a portion of the operating lever, such as is now in common use.

55 In the drawing where similar characters refer to similar parts throughout the differ-

ent views, A designates generally a computing machine including an operating lever B; C a stand therefor including uprights D; E a treadle; F an adjustable support therefor; G a coupling detachably secured to lever B; and H a device, such as a chain, for imparting movement of treadle E to coupling G.

In the example shown, a computing machine A is of that type provided with a detachable operating lever B having a handle 7 and a stem 8, the axis of which is coincident with the axis of oscillation of the lever, this stem 8 extending through a glass 70 wall 9, forming the side wall of the computing machine. It is understood that this lever is used in the operation of the computing machine, after suitable keys 10 have been depressed, for the purpose of setting 75 the machine according to the keys depressed. The stand C may be of any suitable type in the example shown, being provided with caps 11 receiving the extensions 12 at the lower portion of the machine, as is now common practice. The uprights D serving as 80 legs of the machine, are securely braced by cross members 13 and 14.

Referring now to the treadle E, it may comprise a main body portion or board 15 85 to which is secured, at its lateral margins, arms 16 and 17, said arms provided with sleeves 18 to fit about a shaft 19, which in turn is supported by suitable brackets 20 adjustably connected with the uprights D. 90 In the example shown, these brackets comprise a U-shaped body portion 21, one stem, that designated 22 of each bracket being longer than the other stem 23, said body portion fitting about the uprights D; and, 95 a bolt 24 and a nut 25 extending through the stems 22 and 23 in a manner that the body portion 21 may be clamped on said uprights. The shaft 19 has engagement with and is supported by the stems 22 of 100 said brackets, and collars 26 having set screws 27 may be provided about the shaft 19 to prevent longitudinal movement thereof with respect to the brackets. The sleeves 18 may also be provided with set screws 28, 105 enabling the treadle E to be adjustably secured to shaft 19. It is to be observed that, by providing a treadle E with adjustable support F, said treadle may be adapted to various makes of stands C, and the treadle 110 may be adjusted to that position most convenient for the operator by merely releas-

ing set screws 28 and moving the arms with the body portion 15 longitudinally of shaft 19, until in the position desired whereupon the set screws 28 may be turned tight. The 5 adjustable support F may also be moved longitudinally of the uprights D so that the treadle E is positioned in a plane most convenient for use by the operator.

As to the coupling G, it comprises a main 10 body portion 29 including arms 30 and 31 disposed at substantially a right angle, and an arcuate connection 32 joining the arms 30 and 31 at their ends opposite from the point of juncture; and, means 33 for detachably securing said main body portion 15 to the lever B.

While lever B may be of any suitable shape, it is provided with a longitudinally extending rib 34 extending from the handle 20 7 to a disk-like enlargement 35 coaxial with the axis of operation of said lever, in the example shown. The arm 30 of body portion 29 is provided with a depression 36 in its face formed to the contour of the outer and 25 side faces of lever B. That is, said depression embodies a groove 37 into which the rib 34 may extend; a recess 38 for receiving the disk-like enlargement 35; and, an enlarged groove 39 open to groove 37 into which the 30 main body portion of lever B fits, and so that the rear face of said lever is flush with the rear face of body portion 29. The means 33 may comprise a bar 40 pivotally connected to body 29 adjacent one margin of the depression 36, as by screw 41 and detachably secured adjacent the other margin of said depression, as by screw 42, so that, by removing one of said screws, the bar may be 35 swung to the position shown in Fig. 4 enabling the lever B to be placed into operative relation with the coupling, after which the bar 40 is swung to extend across the rear face of the lever, and is secured in place by the screw. By this construction, the coupling 40 is held against movement longitudinally of the lever and against swinging action, so that there is no danger of it engaging the glass wall 9 of the computing machine. It is preferred to form the arms 30 and 31, 45 and the connection 32 of one integral mass, a perforation 43 being provided at the end portion of arm 31 opposite from its juncture with arm 30 to receive a suitable link 44 with which the device G has connection. 50 The arm 31 not only serves as a means whereby the device H is operatively connected with the coupling, but also gives weight to the body 29, laterally of its pivot point and acting in conjunction with the connection 32 facilitates oscillation of the coupling and lever. The arcuate connection 32 also presents a rounded periphery, so that if it is desired to operate the lever B by grasping the handle 7 instead of operating 55 the treadle E, there is no obstruction or pro-

truding part which would be likely to engage the sleeve of the operator or otherwise interfere with manual operation of the lever, the operator using his hand instead of foot action.

With regard to the device H, it may consist of a chain detachably secured to link 44 and to an extension 45 of arm 17, said arm provided with a perforation 46 into which the device H extends. The device H, being flexible, is trained from its connection with treadle E, exteriorly of the cross piece 14, and interiorly of cross piece 13, where it is out of the way and does not act as an obstruction when the machine is not in use.

The operation of the attachment is as follows:

Having been adjusted so that the treadle E is positioned in the most convenient plane for use by the operator, upon depressing the treadle, the coupling G is swung about the axis, carrying lever B therewith. When pressure upon the treadle is released, the lever B swings back to the normal position and the machine is ready for the next operation. It is to be observed that, with an attachment of this character it is not necessary for the operator to remove his hand from above the keys 10, so that operation of the computing machine is facilitated. In practice it has been found that an operator becomes so accustomed to utilizing a treadle that he subconsciously actuates the treadle after the desired keys have been depressed and is in readiness to depress the next combination of keys without moving the fingers from above the key-board. There is no danger of the machine becoming marred, nor the side wall 9 damaged inasmuch as the coupling G is rigidly secured to the lever B. Adjustment is also possible to adapt the attachment to various types and sizes of stands, as is obvious from an inspection of the drawings.

Changes in details may be made without departing from the spirit or scope of my invention; but,

I claim:

1. In an attachment for a computing machine, the combination with an operating lever for the machine, of a segmental coupling frame having a longitudinal seat in one radial portion thereof adapted to receive said lever longitudinally therein, securing straps detachably attached to said radial portion and adapted to span said seat and engage said lever for retaining the lever in the seat, said recess shaped to snugly fit said lever to prevent play of the lever with respect to the coupling, a treadle, and a connection between said treadle and the outer portion of said segmental coupling frame.

2. In an attachment for a computing machine, the combination with an operating

lever for the machine, of a segmental coupling frame having a longitudinal seat in one radial portion thereof adapted to receive said lever longitudinally therein, said seat being shaped to conform to the configuration of the inner side of said lever to prevent movement of the lever independently of the segmental frame, securing straps detachably attached to said radial portions and 5 adapted to clamp said seat and engage said

lever for retaining the lever in the seat; a treadle pivotally supported forwardly of the pivot of said lever and extending rearwardly, and a flexible connection between the outer portion of said segmental coupling frame and the free end of said treadle, the connection between said flexible member and said treadle being substantially directly downward of the pivot of said lever. 15

SAMUEL B. WILSON.
